CLAIM

The ornamental design for a shoe sole, as shown and described.

DESCRIPTION

FIG. 1 is a bottom front perspective view of a shoe sole showing my new design;

FIG. 2 is a bottom rear perspective view thereof;

FIG. 3 is a bottom view thereof;

FIG. 4 is a left side elevational view thereof;

FIG. 5 is a right side elevational view thereof;

FIG. 6 is a front view thereof; and,

FIG. 7 is a rear view thereof.

The broken line showing of the top edge and the remainder of the shoe sole is for illustrative purposes only and forms no part of the claimed design.

The broken lines immediately adjacent to the solid lines throughout the views represent the boundaries of the design while the broken lines themselves form no part of the claim.
